(57) **CLAIM**

The ornamental design for a carry cage for tube cleaning machine, as shown and described.

DESCRIPTION

This application is a division of application Ser. No. 29/421, 241 filed Jun. 18, 2012, now design U.S. Pat. No. D722,737.

FIG. 1 is a perspective view of carry cage for tube cleaning machine, showing our new design;

FIG. 2 is a front elevation view thereof;

FIG. 3 is a rear elevation view thereof;

FIG. 4 is a side elevation view thereof, the opposite side being a mirror image;

FIG. 5 is a top plan view thereof; and,

FIG. 6 is a bottom plan view thereof.

The portions of the carry cage for tube cleaning machine shown in broken lines form no part of the claimed design.
